UNITED STATES PATENT OFFICE.

ULRICH EBERHARDT, OF NEWARK, NEW JERSEY.

SHAPING-MACHINE.

SPECIFICATION forming part of Letters Patent No. 402,574, dated May 7, 1889.

Application filed December 8, 1888. Serial No. 292,991. (No model.)

To all whom it may concern:

Be it known that I, ULRICH EBERHARDT, a citizen of the United States, residing at Newark, Essex county, New Jersey, have invented 5 certain new and useful Improvements in Crank-Planer Levers, fully described and represented in the following specification and the accompanying drawings, forming a part of the same.

10 This invention relates to an improved lever-connection between the crank and the ram of a crank-planer or shaping-machine; and it consists, partly, in a crank-lever having a slot in one side only for the reception 15 of the crank-pin box, and formed with a web upon the opposite side to strengthen the arm, with an aperture through such web to give access to the crank-pin.

It also consists in the combination, with the 20 crank-pin and the ram, of a lever provided with a slot for the crank-pin, a head at one end thereof rounded at opposite sides, and connected with the lever by a neck having flanges projected at opposite sides, and a pair 25 of ears or lugs attached to the ram and fitted to the opposite sides of the head between the said flanges.

30 In the annexed drawings the lever, which embodies all the improvements, is shown in connection with the crank-pin and the ram, as the latter are the only parts of the shaping-machine that co-operate therewith.

35 Figure 1 is a side elevation of the crank-pin and its driving-gear, the ram, and their connecting-lever. Fig. 2 is a view of the under side of the ram. Fig. 3 is an edge view of the lever; and Fig. 4 is a vertical section of the lever, the ram, and the frame of the shaping-machine, taken on line $x-x$ in Fig. 1, 40 with the gearing for the crank-pin (not shown) in section.

The crank-pin a is shown attached to a segment, b , pivoted upon the face of a gear-wheel, c , and movable thereon by suitable means— 45 such as are described in United States Patent No. 241,488, issued May 17, 1881—by which the crank-pin may be moved to and from the center of the crank-shaft d to vary the stroke of the ram.

50 In Fig. 4 the frame of the shaping-machine is shown in section, consisting of two plates,

F F' , supporting ways w for the ram; but it is obviously immaterial to the present invention how the frame be constructed. The gear c is shown journaled in a bearing, c' , upon 55 the plate F , and rotated by a gear, c^2 , upon a shaft, c^3 .

r is the ram, provided with slot r' , in which is fitted a bolt, s , carrying a forked piece having two ears, t . 60

f is the lever, movable with one flat side adjacent to the crank-pin a , and oscillated by the motion of such pin upon a pivot, g , at its lower end. The lever is formed in the side adjacent to the crank-pin with a slot, h , in 65 which the crank-pin box a' slides, and upon the opposite side with a web, i , having an aperture, j , to give access to the crank-pin. The plate F' of the shaping-machine adjacent to the plate i is also formed with an opening, 70 F^2 , to give access to the aperture j in the lever.

e is the head of the lever, rounded at its opposite faces to fit and move between the lugs t , and connected with the lever by a neck, e' . Such neck permits the turning of the head 75 between the lugs when the crank imparts a long stroke to the ram; but it unavoidably weakens the junction of the head and lever;

and the present improvement consists, partly, in projecting flanges from the opposite 80 edges of the neck, at such distance apart as to admit the lugs t between them. Such flanges thus strengthen the union of the head and lever, and offer no interference to the free oscillation of the head between the lugs. 85

Heretofore it has been common to extend the slot h entirely through the lever, which divided the lever into two longitudinal parts, which were wholly separated, and thereby materially weakened. By forming the slot in 90 only one side of the lever and closing the opposite side with the plate i , provided with the aperture j , the lever is strengthened much more than it is increased in weight, and is rendered much more rigid when in operation 95 without materially increasing its cost or the labor of finishing the slot. The aperture j affords the necessary access to the crank-pin for lubrication or examination, while the opening F^2 in the plate or frame F' of the 100 shaping-machine affords convenient access to the aperture j . The plate F , which repre-

sents one side of the shaping-machine frame, is indicated in Fig. 1; but the plate F' , through which the aperture F^2 would be formed, is removed in Fig. 1 to expose the ram and the other parts connected with the invention.

It is obvious that where the box slides in the slot, at the same time that it presses against the side of the slot the whole pressure transmitted from the crank-pin is received by the metal at one side of the slot only, and that only one-half of the metal in the lever is directly employed in transmitting the movement to the same if the slot be extended all the way through the lever and the opposite 15 sides of the slot be disconnected. The object of the web i is therefore to connect the metal bars of the lever f , which form the opposite sides of the slot, and thus enable each bar to assist the other in bearing the strain imposed upon it. As the crank-pin rotates through a whole revolution in such constructions, the pressure operates alternately upon the opposite sides of the slot, and when the slot extends all the way through the lever it has 20 been common for such pressure to break or crack the metal at one side of the slot for want of sufficient strength. By the use of the web i , or any equivalent connection between the bars at the opposite sides of the slot, the strength of both sides is combined, and double the rigidity and strength is secured without at all enlarging the bars themselves. It is therefore immaterial whether the web wholly closes one side of the slot, as 25 is evidenced by the formation of the aperture j for oiling the crank-pin and box within the slot. The crank-pin a is shown secured to a sector, b , pivoted near the edge of the gear c , and held in any desired position on the face

of the gear by a segmental gib. The adjustment of the sector b is intended to shift the crank-pin a to or from the shaft d to vary the throw of the lever f ; but the construction of the crank is immaterial to the present invention, although the slot h in the crank-lever f 40 would in every case be formed upon the side adjacent to the crank, whatever the construction of the latter might be.

What is claimed herein is—

1. In a crank-planer, the combination, with the ram r , the crank-pin a , and the crank for driving the pin, of the crank-lever f , formed with the slot h in one side adjacent to the crank, the crank-pin box fitted movably thereto, the web i , connecting the bars upon the opposite sides of the slot, and the aperture j through such web, the whole arranged and operated as and for the purpose set forth.

2. In a crank-planer, the combination, with the ram r , the crank-pin a , and the crank for driving the pin, of the crank-lever f , formed with the slot h in one side adjacent to the crank and having the crank-pin box fitted movably thereto, the web i , connecting the bars upon the opposite sides of the slot, the rounded head e , connected with the lever by the neck e' , the flanges l , projected at opposite sides of the neck, and the lugs t , connected with the ram and fitted to the opposite sides of the head, as and for the purpose set forth.

In testimony whereof I have hereunto set my hand in the presence of two subscribing witnesses.

ULRICH EBERHARDT.
